Patented Feb. 17, 1976

238,887

GAS SAMPLE SYSTEM CONSOLE

Edward A. O'Neal and Gottlieb C. Gaeke, Baton Rouge, La., assignors to Ethyl Corporation, Richmond, Va.

Filed Feb. 4, 1974, Ser. No. 439,006

Term of patent 14 years

Int. Cl. D24—01

U.S. Cl. D32—2 C

FIG. 1.

FIG. 2.

FIG. 3.

FIG. 1 is a perspective view of a gas sample system console embodying our new design;

FIG. 2 is a rear elevational view thereof; and

FIG. 3 is a side elevational view thereof.

We claim:

The ornamental design for a gas sample system console, substantially as shown.
